(57) **CLAIM**

The ornamental design for a remote control box for ships, as shown and described.

DESCRIPTION

FIG. 1 is front, right side perspective view of a first embodiment of a remote control box for ships, showing my new design;

FIG. 2 is a rear, right side perspective view thereof;

FIG. 3 is a right side view thereof;

FIG. 4 is a left side view thereof;

FIG. 5 is a front view thereof;

FIG. 6 is a rear view thereof;

FIG. 7 is a top view thereof;

FIG. 8 is a bottom view thereof;

FIG. 9 is a front, right side perspective view of a second embodiment of a remote control box for ships, showing my new design;

FIG. 10 is a rear, right side perspective view thereof;

FIG. 11 is a right side view thereof;

FIG. 12 is a left side view thereof;

FIG. 13 is a front view thereof;

FIG. 14 is a rear view thereof;

FIG. 15 is a top view thereof; and,

FIG. 16 is a bottom view thereof.

The broken lines in the drawings illustrate environmental material which forms no part of the design.
